UNITED STATES PATENT OFFICE.

OTTO JAEGER AND GEORGE SCHMIEDEL, OF NEW YORK, N. Y.

DESIGN FOR TEXTILE FABRIC.

SPECIFICATION forming part of Design No. 29,654, dated November 8, 1898.

Application filed July 16, 1898. Serial No. 686,186. Term of patent 3½ years.

To all whom it may concern:

Be it known that we, OTTO JAEGER and GEORGE SCHMIEDEL, residing in New York city, county and State of New York, have invented and produced a new and original Design for a Textile Fabric; and we do hereby declare that the drawing accompanying this specification gives and conveys to any one skilled in the art of printing or weaving and manufacturing a clear understanding of the same, of which the following is a description, reference being had to the accompanying drawing, showing the same.

The essential feature of this design for a textile fabric consists of an artistically-outlined group of blocks. In the center of each there is a neatly-arranged figure or a spray

group. The general appearance of the whole pattern is on a plan somewhat of a parallelogram.

The design is intended to be repeated throughout the length and breadth of a cut or web of fabric.

What we claim, and desire to secure by Letters Patent, is—

The design for a textile fabric substantially as herein shown and described.

In testimony whereof we affix our signatures in presence of two witnesses.

OTTO JAEGER.
GEO. SCHMIEDEL.

Witnesses:

E. WHITTEMORE,
FRED P. GOBLE.
